UNITED STATES PATENT OFFICE.

JAMES H. SAGER, OF ROCHESTER, NEW YORK.

DESIGN FOR A TOE-CLIP FOR BICYCLES.

SPECIFICATION forming part of Design No. 25,801, dated July 21, 1896.

Application filed February 24, 1896. Serial No. 580,524. Term of patent 7 years.

To all whom it may concern:

Be it known that I, JAMES H. SAGER, a citizen of the United States, and a resident of the city of Rochester, in the county of Monroe and State of New York, have invented and produced a new and original Design for a Toe-Clip for Bicycles, of which the following is a specification, reference being had to the accompanying drawing thereof.

10 The drawing forming part of this specification is an isometric view of one of my toe-clips.

My design consists in the form given to a sheet-metal toe-clip.

15 The end A has two bands A', bent first in a plane substantially at right angles to the plane of the end A and thence curved upward and backward, forming the graceful curves A² A³. The bands A' diverge from the

point of connection with the end A in planes 20 forming angles substantially symmetrical with reference to the medial plane of the toe-clip. At the point A³ the bands A' unite in a transversely-arranged plate A⁴, having the side arms A⁵ A⁵ and the eye-shaped opening 25 A⁶ transversely formed in the plate A⁴. The exterior contour of the plate A⁴ corresponds to the form of the opening A⁶, and the plate A⁴ (including the arms A⁵ A⁵) is formed in a graceful curve with the ends of its arms lower 30 than the medial line of the plate.

What I claim is—

The design for a toe-clip for bicycles substantially as shown and described.

JAMES H. SAGER.
